DESIGN FOR A CLEANING BRUSH

Clement S. McPhee, Cranston, R. I., assignor to
Everett and Barron Company, Providence, R. I.,
a corporation of Rhode Island

Application November 7, 1938, Serial No. 80,915

Term of patent 3½ years

To all whom it may concern:

Be it known that I, Clement S. McPhee, a citizen of the United States, residing at Cranston, in the county of Providence and State of Rhode Island, have invented a new, original, and ornamental Design for a Cleaning Brush, of which the following is a specification, reference being had to the accompanying drawing, forming part thereof.

Figure 1 is a top plan view of a cleaning brush showing my new design;

Figure 2 is a side elevational view;

Figure 3 is a bottom plan view; and
Figure 4 is an end elevational view thereof.

The brush comprises a body around which is a rubber belt composed of a portion of sponge rubber, which lies along the entire upper side in Figures 1, 2 and 4 and a portion having projecting rubber prongs or teeth which extend from along the bottom side and around the ends.

I claim:

The ornamental design for a cleaning brush, as shown and described.

CLEMENT S. MCPHEE.
